(57) **CLAIM**

The ornamental design for an e-shaped top for a bubble pen, as shown and described.

DESCRIPTION

FIG. 1 is a front perspective view of an e-shaped top for a bubble pen showing my new design;

FIG. 2 is a front elevational view of the present design;

FIG. 3 is a top plan view of the present design;

FIG. 4 is a right side elevational view of the present design;

FIG. 5 is a left side elevational view of the present design;

and,

FIG. 6 is a bottom view of the present design.

The broken line showings of the writing instrument are for illustrative purposes only and form no part of the claimed design.
